ATTORNEY.

FIG. 4.

UNITED STATES PATENT OFFICE

2,090,157

ROAD SIGN

Bryan H. Smith, Berkeley, Calif.

Application October 9, 1935, Serial No. 44,179

2 Claims. (Cl. 40—125)

This invention relates generally to portable and collapsible signs, which are suitable for use on highways to warn motorists.

It is an object of the invention to provide a sign of the above character which can be quickly positioned on a highway, and which can not be readily dislodged or blown down by wind.

Another object of the invention is to provide a road sign which can be collapsed into a relatively compact structure, thus affording a device which can be conveniently carried by motor trucks.

Further objects of the invention will appear from the following description in which the preferred embodiment of the invention has been set forth in detail in conjunction with the accompanying drawing.

Fig. 1 is a rear elevational view, showing a device incorporating the present invention, when fully collapsed.

Fig. 2 is a side elevational view of the device, as positioned upon the surface of a highway.

Fig. 3 is a cross sectional view taken along the line 3—3 of Fig. 2.

Fig. 4 is a cross sectional view taken along the line 4—4 of Fig. 1.

The device as illustrated in the drawing consists of a panel 10, which is preferably formed of three sections 10a, 10b and 10c. Hinges 11 serve to connect adjacent edges of these sections together, so that the side sections 10a and 10c, may be folded behind the center section 10b. The front face of panel 10 carries appropriate lettering, and one of the panel sections, as for example, section 10c, is shown provided with a reflection light signal 12.

In order to form a stable support for the panel 10, means are provided as follows: A pair of spaced rods 13, have a pivotal connection 14 with the upper edge of the center panel section 10b. The other ends of these rods have a pivotal connection 15, with a relatively rigid metal plate 16. The free end of plate 16 is provided with a bent flange 17, which is adapted to interlock with the lower edge of the panel section 10b. For example, the lower edge portion 18 of the center panel section 10b can be extended beyond the adjacent ends of the side panel sections, and doubled back upon itself to form a groove or channel 19, for receiving the flange 17. The outer and lower corners of the side panel sections, also are shown provided with projecting legs 21.

When the sign is positioned upon a highway, as illustrated in Fig. 2, plate 16 serves as a suit-

able platform for receiving a rock 22 or like weight. When properly weighted down in this manner, the sign is capable of withstanding a relatively high wind velocity, without being upset. It will be noted that the weight not only holds the sign down upon the highway surface, but it also serves to more securely interlock the flange 17 on plate 16, with the groove or channel 19 of the panel section 10b. To collapse the sign, it is convenient to first place the panel 10 upside down upon the ground, that is with the printed side of the sign lowermost, after which plate 16 is disconnected with respect to the lower edge of the panel section 10b, to permit rods 13 to be swung upwardly. The panel section 10a is then swung over the back side of panel section 10b, and panel section 10c is swung over the section 10a. Plate 16 is then swung into a common plane with rods 13 as indicated by the arrow in Fig. 2, after which rods 13 together with plate 16 are swung downwardly upon the folded panel sections, as illustrated in Figs. 1 and 4.

It will be evident that the sign when collapsed, forms a compact structure which can be conveniently carried by motor trucks. When required it can be readily positioned on the highway to serve as a desired warning to motorists. The parts of the collapsible supporting means, including rods 13 and plate 16, are connected to the central panel section, leaving the side panel sections free to be collapsed. When the sign is erected, the side panel sections are held in proper position by the corner legs 21.

I claim:

1. In a portable highway sign, a plurality of panel sections hingedly connected together, whereby the sections can be folded upon each other or opened out into a common plane, and collapsible supporting means for retaining the opened panel sections in generally upright position, said last means including an element having its one end pivotally connected with the upper edge of one of said panel sections, a plate pivotally connected to the other end of said element, and means for interlocking the free end of said plate to the lower edge of said one panel section, said plate forming a generally horizontal platform adapted to carry a weight.
2. In a portable sign, three panel sections hingedly connected together, whereby the two side sections can be folded upon the central section or can be opened to bring the sections in a common plane, and collapsible supporting means

for retaining the opened panel sections in generally upright position, said supporting means including an element having its one end pivotally connected to the upper edge of the center panel section, a plate having its one end pivotally connected to the other end of said element, and means for releasably interlocking the

free end of said plate to the lower edge of the center panel section, whereby the plate forms a lower horizontal platform for receiving a weight, said supporting means being collapsible upon the folded panel sections. 5
